(57) **CLAIM**

The ornamental design for a holder for a mobile device, as shown and described.

DESCRIPTION

FIG. 1 is a left, front, top perspective view of a holder for mobile device showing our new design in a first configuration;

FIG. 2 is a front view thereof;

FIG. 3 is a rear view thereof;

FIG. 4 is a top view thereof;

FIG. 5 is a bottom view thereof;

FIG. 6 is a right view thereof;

FIG. 7 is a left view thereof;

FIG. 8 is a left, front, top perspective view of the holder for mobile device of FIG. 1, shown in a second configuration; and,

FIG. 9 is a front view of the holder for mobile device of FIG. 1, shown in a second configuration, wherein, broken lines illustrate portions of the holder for mobile device that form no part of the claimed design.
